UNITED STATES PATENT OFFICE

SAMUEL COHEN, OF BROOKLYN, NEW YORK, ASSIGNOR TO GENERAL INSTRUMENT CORPORATION, OF NEW YORK, N. Y., A CORPORATION OF NEW YORK

VARIABLE CONDENSER

Application filed August 13, 1931. Serial No. 556,888.

My invention relates broadly to electrical condensers and more particularly to the construction of multiple variable electrical condensers having means for compactly 5 mounting a compensating or trimmer condenser adjacent each of the sets of rotor and stator plates in the multiple variable condenser.

One of the objects of my invention is to 10 provide a construction of multiple variable condenser having a pressed metal chassis including a bottom portion and upstanding side wall portions with parts of the side wall portions pressed into different planes 15 for supporting compensating condenser units adjacent each of the sets of multiple variable condensers.

Another object of my invention is to provide a construction of multiple variable condenser having a supporting chassis with the side walls thereof pressed into different vertical planes and supporting parts of a compensating condenser individual to each of the variable capacity units constituting the 25 multiple variable condenser.

Still another object of my invention is to provide a compact construction of multiple variable condenser including a chassis arranged to support a multiplicity of variable 30 condenser units, the side walls of the chassis having a portion thereof offset one from another for providing mounting means for a compensating condenser adjacent each of the variable condenser units, the compensating 35 condensers being so mounted that the parts thereof are entirely shielded by laterally extending electrostatic shields forming part of the condenser chassis.

A further object of my invention is to 40 provide a construction of multiple variable condenser, having a chassis with opposite side walls wherein diametrically opposite apertures are arranged in the side walls and integrally connected tongues projected up- 45 wardly from the bottom of the chassis into a plane parallel with the plane of the side walls but offset therefrom for a distance equal to the thickness of a supporting panel which lies within the plane of the side walls 50 and forms an insulated suspension means for

the stator plate units and for the compensating condenser units.

Other and further objects of my invention reside in the compact construction of a multiple variable condenser as set forth more 55 fully in the specification hereinafter following by reference to the accompanying drawings, in which:

Figure 1 is a side elevation of the multiple variable condenser structure of my invention; Fig. 2 is a plan view showing the arrangement of parts of the multiple variable condenser shown in Fig. 1; Fig. 3 is another side elevation of the multiple variable condenser taken from a position opposite to 60 that at which the view in Fig. 1 is taken; Fig. 4 is a lateral cross-sectional view taken through the condenser on line 4-4 of Fig. 2; and Fig. 5 is a fragmentary sectional view taken through the condenser on line 65 5-5 of Fig. 1.

Referring to the drawings in detail, the condenser chassis is indicated at 5 having a bottom portion and upstanding side wall portions. There are a plurality of plate 75 members extending laterally of the condenser chassis such as represented by reference characters 1, 2, 3 and 4. Plates 1 and 4 constitute end plates for the condenser chassis while plates 2 and 3 constitute electrostatic shields disposed intermediate the sets of rotor and stator plates constituting each of the variable condenser units. A rotatable shaft 6 extends through the electrostatic shields 2 and 3 and is journaled in the 80 end plates 1 and 4, the journals being represented similarly at 1a and 4a in the end plates 1 and 4, respectively. The rotatable shaft 6 carries sleeve members 7, 8 and 9 which are grooved to support sets of rotor 85 plates represented at 20, 21 and 22. The sets of rotor plates are aligned to be interleaved with the sets of stator plates 10, 11 and 12. The stator plates are arranged laterally of the chassis and supported by 90 means at each side thereof in the form of sets of insulated panel members 23, 24 and 25, as shown. The side walls of the condenser chassis are represented at 5a and 5b. These side walls are provided with dia- 95

100

metrically opposite apertures 5c therein. These apertures are partially closed by an upstanding tongue 5d which is bent from the material of the chassis 5 into a plane offset from the plane of the upper portion of the side walls 5a and 5b of the condenser chassis as shown. The exterior surface of the upstanding tongues 5d have their exterior faces extending in the same plane as 10 that in which the interior faces of the associated side wall 5a or 5b extends. That is to say, the tongues 5d which integrally connect with the chassis 5 are bent into a position offset from the interior surface of 15 the upstanding side walls 5a and 5b for a distance equal to the thickness of the side wall. The tongue 5d serves as a carrier for the associated insulated panel member.

As shown in Fig. 4 the insulated panel 23 is riveted at 23a to the upstanding portion of 5d. The panel 33 projects upwardly and substantially fills the space provided by the aperture 5c in the side wall of the condenser chassis. The insulated panel 23 is 20 apertured adjacent the top thereof for the passage of screws 26 which pass through the insulated panel and through the channel shaped member 27 and are secured in position by means of nuts 28. The channel shaped member 27 thereon has diametrically opposite supports for the edges of the sets of stator plates 10, 11 and 12, arranged in such position that the rotor plates may be interleaved therewith. In order to 25 provide for connection to the sets of stator plates, lugs 26a may be secured under the heads of screws 26 at one side of the condenser chassis. At the other side of the condenser chassis I provide a mounting for 30 the compensating condenser for each condenser unit. The compensating condenser is constituted by a plate member 29 through which screws 26 pass for mechanically mounting the plate member 29 and establishing 35 electrical connection between plate member 29 and the sets of stator plates. The plate member 29 has a capacity area at the upper portion thereof which lies immediately adjacent the upper portion of the side wall 5b. An aperture is provided in the upper portion of plate 29 for the passage 40 of an adjusting screw 30 which enters the side wall 5b and is adjustable against plate 29 for varying the spacial relation between plate 29 and the side wall 5b. A dielectric sheet as shown at 31 extends between the plate 29 and the side wall 5b and is supported by laterally projecting tongues 29a on plate 29 as well as by means of adjusting 45 screw 30. Plate 29 has sufficient resiliency to normally tend to force plate 29 away from the side wall of the condenser. However by turning adjusting screw 30 the spacial relation between plate 29 and the side wall 5b may be decreased thereby in-

creasing the capacity of the compensating condenser. Adjustment of the compensating condenser permits the maximum to minimum capacity ratio of each condenser section to be fixed thereby enabling the condenser to be efficiently matched with the tuning circuit in which it is employed in an adjustably tuned amplifier system. Electrical connection is established with plate 29 of the compensating condenser and with the associated stator plates with the projecting lug 29b, arranged as illustrated. The fact that plate 29 is directly connected with the stator plates, places the compensating condenser effectively in shunt with each condenser unit inasmuch as the sets of rotor plates are connected to the condenser frame of which the side 5b is an integral part.

It will be observed that the insulated panel members are so supported by the upstanding tongues 5b that they lie in the plane of the side wall of the condenser chassis. This arrangement is possible because of the arrangement of the tongues 5d which have their exterior surfaces extending in a plane coincident with the plane of the interior surfaces of the side walls of the condenser chassis. The insulated panel member has a thickness substantially equal to the thickness of the wall of the condenser chassis and so occupies a space substantially within the limits of the thickest dimensions of the side walls. The mounting of the compensating condenser is in this way arranged so compactly that all parts of the compensating condenser lie between the adjacent electrostatic shields and closely conform with the lateral dimensions of the condenser. This facilitates quantity production of condensers in manufacture and simplifies assembly, installation and wiring of the condenser in circuit with the amplifier system.

While I have described my invention in one of its preferred embodiments I desire that it be understood that modifications may be made and that no limitations upon my invention are intended other than are imposed by the scope of the appended claims.

What I claim as new and desire to secure by Letters Patent in the United States is as follows:

1. In a multiple variable condenser, a condenser chassis having a bottom portion and upstanding side wall portions, said side wall portions being apertured in diametrically opposite positions, tongues integrally connected with the bottom of said chassis extending vertically therefrom in a plane inwardly offset from the plane of the side wall of said chassis for a distance equal to the thickness of the side wall portions of said chassis, sets of stator plates extending laterally of said chassis, insulated means supported by opposite tongues and con-

5 nected with opposite ends of said stator plates and extending in the plane of the side wall portions of said chassis for suspending said stator plates laterally of said chassis, and a trimmer condenser plate carried by said insulated means in coacting relation to the side wall of said chassis.

10 2. In a multiple variable condenser, a condenser chassis having a bottom portion and upstanding side wall portions, said side wall portions being apertured in diametrically opposite positions, tongues integrally connected with the bottom of said chassis extending vertically therefrom, said tongues 15 being disposed in a plane parallel to the plane of said side walls but inside the limits of said side walls with the outside face of said tongues disposed in a plane coinciding with the plane of the inside face of said side wall portions, an insulated plate connected with each of said tongues and extending vertically in a position filling the apertures in said side walls, sets of stator plates suspended between opposite insulated plates in 20 a position adapted to be interleaved by sets of rotor plates adjustably mounted with respect thereto, and a trimmer condenser plate carried by said insulated means in coacting relation to the side wall of said chassis.

25 3. In a multiple variable condenser comprising a condenser chassis and including a bottom portion and a pair of opposite side wall portions, the side wall portions being apertured at opposite positions, tongues integrally connected with said bottom portion and extending vertically upwardly therefrom to a position within the apertures in said side walls, the exterior surface of said 30 tongues extending in a plane coincident with the plane of the interior surface of the side wall of said condenser chassis, an insulated plate attached at its lower end to each of said tongues, laterally extending sets of stator plates within said condenser chassis and connections between opposite ends of said stator plates and the upper portions of said insulated plates for suspending said stator plates, a compensating condenser having an adjustable plate supported by each of said insulated plates and coacting with said side wall portions, and a rotatable shaft journaled in said condenser chassis and carrying a plurality of sets of rotor plates 35 thereon adapted to be interleaved with said sets of stator plates.

40 4. In a multiple variable condenser a condenser chassis comprising a bottom portion and vertically extending side wall portions, sets of stator plates extending laterally of said chassis, a rotor shaft journaled in said chassis, sets of rotor plates carried by said rotor shaft and adapted to be variably interleaved with said stator plates, said side 45 wall portions being cut to form apertures

aligned with opposite ends of said stator plates and tongues integrally connected at their lower ends with the bottom portion of said chassis and extending vertically therefrom back of lower portions of the apertures 70 in a plane inwardly offset from the plane of the side walls by a distance equal to the thickness of the side walls of the chassis, insulated panels having their lower end portions secured against outer faces of said tongue and extending vertically upwardly in a position filling each aperture, said insulated panels each having a thickness equal to the thickness of the wall of said chassis and means extending through said panels 75 for suspending the said sets of stator plates from the opposite ends thereof, and a compensating condenser having an adjustable plate supported from certain of said insulated panels and coacting with the side 80 wall portion of said chassis.

85 In testimony whereof, I affix my signature.

SAMUEL COHEN.
